UNITED STATES PATENT OFFICE

EDWARD J. DACEY, OF PHILADELPHIA, PENNSYLVANIA, ASSIGNOR TO CROMPTON & KNOWLES LOOM WORKS, OF WORCESTER, MASSACHUSETTS, A CORPORATION OF MASSACHUSETTS

AXMINSTER LOOM

Application filed August 12, 1939. Serial No. 335,344.

This invention relates to Axminster looms and it is the general object of the invention to provide an improved form of support for the tube frames whereby the latter will move without excessive vibration when the chains 5 transporting them move around sprockets.

Axminster looms customarily employ a large number of tube frames each of which is provided with a spool having variously 10 colored tuft forming yarns wound thereon. These tube frames are mounted on and move with a pair of spaced transporting chains which are given periodic movements by means of a pair of sprockets on the so-called 15 pull-over shaft. It is present practice to provide each end of the tube frame with a tongue which extends between the members of a double link on the transporting chain and to hold the tube frame to the chain by 20 some form of hook. As a result of this construction the tube frame is permitted to move through a limited angle with respect to the chain and as the tube frame passes from one side to the other over the center 25 of a sprocket it will be given a sudden movement. As a result of this quick movement there is considerable wearing on the tongues and hooks with occasional breakage of the latter.

It is an important object of my present invention to provide a pivotal connection between the tube frame and the transporting chain so that the tube frame may hang down 30 by gravity for all of its positions with respect to the path along which it travels. The sprockets and shafts therefor are so designed that as the frames move over the sprockets they will be free to hang downwardly without objectionably interfering 35 with the axle or shaft of the sprocket. In this way the tube frame is spared all sudden jars or shocks which have heretofore lessened the life of the heads or hooks by means of which the tube frames are attached to the chains.

It is a further object of my present invention to provide improved loom operating mechanism which engages each tube frame as it reaches weaving position to effect a relative movement between the chain

support and the tube frame so that the latter may be detached from the chain and moved toward tuft forming position. As shown herein I choose to use cup-like receptacles of V-shaped carriers or pockets on the tube frames and the mechanism operates first to lift the fingers out of the cups and then move the tube frames laterally to a position permitting their descent to tuft forming position without interfering with the chain or any part carried thereby. 55

It is a further important object of my present invention to provide means whereby the yarn delivering tubes of the tube frame always point downwardly. I find 60 that in usual practice long tube frames sag, sometimes with the yarn delivering tubes pointing downwardly, and at other times with the yarn delivering tubes pointing upwardly. The tube frames alternate from 65 one of these positions to the other several times as they pass over the guide sprockets. As a result of this alternating sagging first in one direction and then in the other the 70 yarn in the tubes works back toward the spool, thus causing low rows of piles in the woven cloth. With the structure set forth hereinafter the yarn tubes point downwardly or substantially so throughout their whole 75 travel, and if there is any sagging of tube frames it is always in the same direction with respect to the yarn delivering tubes. 80

With these and other objects in view which will appear as the description proceeds, my invention resides in the combination and arrangement of parts hereinafter described and set forth in the claims. 85

In the accompanying drawings wherein a convenient embodiment of my invention is set forth, 90

Fig. 1 is a side elevation of the upper part of a loom having applied thereto the chain embodying my present invention,

Fig. 2 is a view on an enlarged scale of 95 a portion of the construction shown in Fig. 1, parts being broken away for the sake of clearness,

Fig. 3 is an enlarged detailed front elevation of chain and tube frame construction taken in the direction of arrow 3, Fig. 1, 100

Figs. 4 and 5 are detailed vertical sections on lines 4—4 and 5—5, respectively, of Fig. 3,

Fig. 6 is a detailed vertical section on line 5 3—6 of Fig. 4,

Fig. 7 sets forth a portion of the blank from which the chain engaging element of the tube frame is fashioned,

Figs. 8, 9 and 10 show diagrammatically successive positions assumed by the tube frame transferring mechanism, and

Fig. 11 is a detail top plan view looking in the direction of arrow 11, Fig. 2.

Referring particularly to Fig. 1 I have shown a loom frame 10 in which is journaled a pullover shaft 11 having secured thereto a ratchet wheel 12 engaged by pull pawl 13 mounted on an arm 14 which pivots around the axis of shaft 11 and is pivotally connected to an actuating link 15. The latter is connected to lever 16 pivoted as at 17 to the loom frame. A second link 18 attached to the lever 16 is connected to a cam lever 19 so that as the latter moves up and down under influence of track cam 20 the pawl will be moved first to the right and then the left as viewed in Fig. 1.

Shaft 11 has secured thereto a pair of sprockets 21 one of which is shown herein. 30 The upper portion of the loom frame 10 supports other sprockets certain of which as designated at 22 may be of relatively large diameter and mounted on cross shafts 23, while other of the sprockets 24 may be 35 of less diameter. A pair of transporting chains 25 and 26 which are mounted, respectively, at the right and left hand sides of the loom are trained over the sprockets and are the means by which the tube frames 40 27 are supported and moved progressively through the loom to present one tube frame at a time to the fabric for the formation of the rows of tufts.

At each side of the loom there is a clutch 45 28 supported on the adjacent transerrer arm 29 by means of a pivot stud 30 on the arm and about which the clutch may rotate. A rod 31 is connected to each clutch at a point removed from the center of the stud 50 30. Each transerrer arm is pivoted about a supporting stud 32 and is moved by means of a rod 33 to have movements transverse of the loom or in directions parallel to the pullover shaft.

55 The rod 31 is connected to a rock lever 34 moving about a shaft 35 extending across the loom, said lever 34 being connected by means of link 36 to an actuating lever 37. The latter is pivotally connected as at 38 to a larger lever 39 which is pivoted by means of stud 40 to the frame of the loom. Stud 32 and shaft 35 are mounted on carriers 41 which are attached as at 42 to upright rods 43 the lower ends of which are 65 pivotally connected as at 44 to the relatively

heavy levers 39. The latter is provided with a cam roll 45 which engages a cam 46 mounted on the driving shaft 47 secured thereto by means of a key 48. It is to be understood that a cam lever 39 is located at each end of the loom.

The matter thus far described and operation thereof is common in Axminster looms and forms no part of my present invention. The pullover pawl 13 is set forth in patent to Wyman No. 543,820 while the operation of the cross rods 33 is as set forth in patent to Smith and Skinner No. 186,374.

As previously stated the present invention relates more particularly to the connection between the tube frame and the chain and is aimed to provide a construction which will obviate the quick and sudden movements of the tube frame with respect to the chain. Each of my improved chains is formed of a plurality of double links 50 between which extend single links 51. As shown particularly in Fig. 6 I provide the double link 50 with a pin 52 on which is pivotally mounted a carrier or receiver 53. As shown in Fig. 5 the carrier has upwardly and outwardly inclined surfaces 54 which in effect form a V-notch, said surfaces being substantially perpendicular to the vertical web 55 of the carrier.

Each end of the tube frame is provided with a chain engaging arm 56 the upper end of which is formed as shown in Fig. 5 with a substantially horizontal portion 57 from the ends of which extend downwardly and inwardly inclined wings 58. The latter form a V-shaped finger which fits the previously described notch in the carrier.

In forming the arm 56 I stamp the same from flat stock to the shape substantially shown in Fig. 7. The blank is formed with the two lateral wings 58 which extend from opposite sides of the horizontal portion 57, said wings being bent downwardly along the dotted lines indicated at 60 and the structure thus formed then being given a quarter bend along another line of folding 61 to provide a structure substantially the same as shown in Figs. 3, 5 and 6.

It will be understood that the center of gravity of the tube frame will always be below the axis of the carrier 55 or pin 52, with the result that the tube frames will hang down in a vertical direction from the carriers. The radius of the sprockets 22 will be such as to permit the tube frames to hang downwardly without causing interference between them and the shafts 23 on which the sprockets 22 are mounted. The tube frames are always free to hang downwardly while the chains are going around the sprockets, resulting in an easy movement of the frames.

In the particular form of my invention set forth herein it is necessary in order to

- move the tube frame from the chain to weaving position, first to raise the same so that the head of the arm 56 will be above the carrier and then to move the heads laterally so that they will be out of vertical alignment with the carriers. These movements are brought about through the previously described clutches and transerrer arms. The raising movement is accomplished by providing the cam 46 with a tappet 60 which is of sufficient length to hold the tube frame in a slightly raised position while it is being moved laterally out of vertical alignment with the carriers. 10 The lateral movement is effected through a large rocking shaft 61 mounted in bearing 62 secured to the loom frame. This shaft preferably extends across the loom and has operative contact with the transerrer arms at each end of the loom. An operating arm 63 is keyed to the shaft 61 and connected by means of rod 64 to a lever 65 having a roll 66 which engages with the rocking cam 67. This latter cam is keyed to the cam 25 shaft 47 to rotate with the cam 46 and has a low dwell 68 which when in contact with the roll 66 will permit the shaft 61 to be rocked in a counterclockwise direction as viewed in Fig. 2 under influence of spring 30 39. In this position the clutches are in alignment with the tube frame to start the removing operation. Cam 67 is provided with a rise 70 the effect of which is to depress the lever 65, when the cam rotates in the direction of arrow α , thereby rocking the shaft 61 in a clockwise direction as viewed in Fig. 2. 35 It is to be understood that each carrier arm 41 is pivotally connected to offset 71 formed in the shaft 61 and that each said offset passes between a cap 72 and a lower bearing portion 73 of the arm 41. The cap is held to arm 41 by means of bolts 74, from which it will be seen that the carrier 41 and all the parts mounted thereon are capable 45 of angular movement relative to the shaft 61. 75 The cam 67 is provided with a high dwell in the cam 46, and the latter is provided with a second tappet 77 at the end of the high dwell 76, this tappet performing the reverse function of that accomplished by the first described tappet 60. 50 As seen in Fig. 3 the tube frame designated generally at 27 comprises the yarn spool S rotatable in a part of arm 56 above a bar B to which are secured and from which depend the tuft yarn tubes T, the latter hanging downwardly at all times 55 throughout the travel of the chains around their sprockets. 60 From the structure herein described it is believed that the operation will be apparent. After the clutches have moved inwardly to 65 the position shown in Fig. 2 and in dotted lines, Fig. 8, in engagement with the tube frames they will be raised by means of tappet 60 and lever 39, which lift carrier 41 to the position shown in Fig. 8. Continued rotation of shaft 47 causes cam 67 on 70 cam 67 to lower lever 65, thereby rocking shaft 61 in a right hand direction. This moves the carrier 41 rearwardly to the position shown in Fig. 9, the clutch having moved from the dotted to the full line position and the arm 56 still being raised to clear the chain carried pockets 53. After the tube frame has been moved out of vertical alignment with the pockets, roll 45 will move down along surface 78 to permit the tube frame to descend to the tuft-forming position shown in dot and dash lines in Fig. 2, and also in Fig. 10. This latter figure shows the progress of the clutch, the dotted lines showing the position after being raised, the dot and dash position showing the clutch moved rearwardly, and the full lines showing the clutch in low position. It is during this low position that a cam 80 engages the lever 37 to cause upward rocking of the same with resultant endwise movement of the rods 31 to pivot the clutches about studs 30. It is to be understood that there are two levers 34 which are secured to the shaft 35 running across the loom. 90 After the tuft forming operation is completed the operation described takes place in reverse order, surface 81 raising the transerrer arms, the roll 66 meantime still remaining on the dwell 75 of the cam 67. Lever 39 will be supported by the short tappet 77 after being raised to its highest position and during this time the lowering face 82 of the cam 67 will arrive over the roll 66 and the latter will start to move upwardly under influence of spring 69. This upward movement with consequent movement of the tube frame to its extreme left position as viewed in Fig. 2 takes place while the carrier arm 41 is supported by the tappet 77, but as soon as the heads of the transerrer arms are in substantial vertical alignment with the V-notch in the carriers of the chain, the roll 45 will move downwardly to the dwell 76, thereby lowering the tube frame 100 so that the same is returned to its starting position. 105 There is then a spreading action on the part of the transerrer arms 29 so that the latter clear the path along which the tube frames move with the chains, whereupon pull pawl 13 will come into action to bring another tube frame in position to go through the motions already described. 110 By referring particularly to Figs. 1 and 2 it will be seen that the yarn tubes 27 and the tuft forming yarn extending therefrom point downwardly irrespective of the location of the tube frame in the transporting chain and in spite of the fact that the tube 115 120 125 130

frame goes over certain of the sprockets and under others. The effect of this condition is to prevent the yarn from creeping back into the yarn tubes, thereby lessening the chance for the formation of short tufts. Because of the fact that the tube frames are moved downwardly from the chain to tuft forming position it is possible to employ the construction set forth herein which requires the yarn tubes to point downwardly at all times.

From the foregoing it will be seen that I have provided a simple connection between the transporting chains and tube frames whereby the latter may be spared the objectionable vibration which characterizes tube frames at present in use. I believe I am the first to provide the form of connection set forth herein which permits the tube frame to be detached from the transporting chain and move toward tuft forming position, and I do not wish to be limited to the detailed constructions set forth herein. It is sufficient for the purposes of my present invention if means are provided to effect a relative movement on the part of the tube frame arm heads and the carriers to permit the frames to move downwardly without being interfered with by the carriers. It will also be seen that I have provided improved mechanism, such for instance as the cams and rocking shafts 61, to effect a slight displacement of the tube frames to permit the latter to be detached from the carriers. It will further be seen that the yarn tubes point downwardly throughout their travel, thus preventing the formation of low rows of tufts.

Having thus described my invention it will be seen that changes and modifications may be made therein by those skilled in the art without departing from the spirit and scope of the invention and I do not wish to be limited to the details herein disclosed, but what I claim is:

1. In an Axminster loom, a pair of spaced endless transporting chains, a tube frame extending between the chains, detachable pivoted connections between the tube frame and chains capable of turning the frame through a complete revolution relatively to the chains, and means to raise the frame from the connections, move the frame out of alignment with the connections and then lower the frame to tuft forming position, said tube frame supported by the chains at all times when out of tuft forming position.

2. In an Axminster loom, a pair of spaced endless transporting chains, a tube frame extending between the chains, detachable pivoted connections between the tube frame and chains capable of turning the frame through a complete revolution relatively to the chains, and means to cause relative movement between the connections and frame to

cause said connections and frame to be out of vertical alignment, and other means to lower the frame to tuft forming position, said tube frame supported by the chains at all times when out of tuft forming position. 70

3. In an Axminster loom, a pair of spaced endless transporting chains, a tube frame extending between the chains, detachable pivoted connections between the tube frame and chains capable of turning the frame through 75 a complete revolution relatively to the chains and supported thereby throughout the revolution, and means to cause relative movement between the connections and frame to cause said connections and frame to be out of alignment, said means to move the frame to tuft forming position.

4. In an Axminster loom, a pair of transporting chains having intermittent movements, a carrier pivoted to each chain, a tube frame supported in the carriers, a rocking member, supporting arms carried by the member to have holding engagement with the tube frame, means to raise the arms to lift the tube frame out of the carriers, means thereafter to rock the member to carry the tube frame and arms away from the carriers, and additional means providing for lowering the tube frame to tuft forming position. 90

5. In an Axminster loom, a pair of transporting chains having intermittent movements, a carrier pivoted to each chain, a tube frame supported in the carriers, a rocking member, a pair of arms pivotally mounted on the member to have supporting relation with the tube frame, means to lift the tube frame and arms while the rocking member is in one position, means thereafter to rock the member to another position to carry the tube frame and arms away from the carriers on the chains, and means to subsequently lower the arms and tube frame to tuft forming position. 100

6. In an Axminster loom, a pair of transporting chains having intermittent movements, a carrier pivoted to each chain, a tube frame supported in the carriers, a rocking member, tube frame engaging and supporting arms pivotally connected to the member, and a pair of cams, the first cam being operatively connected to the arms and effective to lift the same while the rocking member is at rest, the second cam operatively connected to the rocking member and acting subsequently to the first cam to rock the member to cause movement of the tube frame out of alignment with the carriers, the first named cam subsequently lowering the 110 arms and tube frame to tuft forming position. 115

7. In an Axminster tube frame, a pair of spaced transporting chains having intermittent movements and intervening periods 120

of rest, guides over and under which the chains extend, a carrier pivoted to each chain, the carriers moving with the chains around the guides, a shaft around which the carriers and chains move, the carriers being disposed in aligning pairs relatively to the axis of the shaft, a tube frame having yarn tubes, and a head on each end of the tube frame to have supporting relation with respect to the carrier adjacent thereto, said head being capable of disengagement from the carrier by an upward movement while the chain is in a period of rest, the center of gravity of the tube frames being below the pivoted connections and the yarn tubes projecting downwardly.

8. In an Axminster tube frame, a pair of spaced transporting chains, guides over and under which the chains extend, a carrier pivotally mounted on each chain, the carriers moving with the chains around the guides, the carriers being opposite each other and each carrier having an upwardly opening supporting pocket, a tube frame having yarn tubes, and a supporting element on each end of the tube frame to have supporting relation with respect to the pocket of the carrier, said elements and tube frame being movable upwardly from the carriers while the latter are at rest, the center of gravity of the tube frames being below the pivoted connections and the yarn tubes projecting downwardly.

9. In an Axminster loom, a pair of spaced transporting chains, guides over and under which the chains extend, a pair of carriers having upwardly opening V-shaped notches, the carriers moving with the chains around the guides, said carriers being opposite each other and pivoted to their respective chains, a tube frame having yarn tubes, and a head on each end of the tube frame having a downwardly pointing V-shaped portion, said portions entering the V-shaped notches and being removable therefrom by an upward movement, the center of gravity of the tube frames being below the pivoted connections and the yarn tubes projecting downwardly.

10. In an Axminster loom, a pair of spaced transporting chains, guides over and under which the chains extend, a pair of carriers having upwardly opening V-shaped notches, the carriers moving with the chains around the guides, said carriers being opposite each other and pivoted to their respective chains, a tube frame having yarn tubes, and a head on each end of the tube frame having a downwardly pointing V-shaped portion, said portions entering the V-shaped notches and being removable therefrom by an upward movement, the center of weight of the tube frame being below the axes of the carriers.

11. In an Axminster loom, endless spaced

transporting chains, a tube frame extending between and supported by the chains and having yarn tuft tubes, guides for the chains, the latter passing over certain guides and under others, and connections between the tube frame and chains pivoted to the latter, said connections always assuming substantially the same vertical position when moving over or under the guides with the chains, the center of gravity of the tube frame being below the connections and the tuft tubes pointing downwardly.

12. In an Axminster loom wherein the pile tufts are applied to the fabric from the upper side thereof, endless spaced transporting chains, a tube frame extending between and supported by the chains and having tuft tubes extending downwardly therefrom at all times, upper and lower guides over and under which, respectively, the chains move, and connections between the tube frame and chains movable relatively to the latter but supported thereby, said connections always assuming substantially the same vertical position whether moving over or under the guides with the chains, the center of gravity of the tube frame being below the connections and acting to keep the latter in the said vertical position.

13. In an Axminster loom wherein the pile tufts are applied to the fabric from the upper side thereof, endless spaced transporting chains, a tube frame extending between and supported by the chains and having tuft tubes extending downwardly therefrom at all times, upper and lower guides over and under which, respectively, the chains move, said guides having substantially arcuate portions to engage the chains and supports for the tube frame mounted on and movable relatively to the chains, said supports always assuming a substantially vertical position whether passing over or under the guides with the chains and having supporting relation relatively to the tube frame regardless of the radius of the said arcuate portions, the weight of the tube frame maintaining the supports and tube frame in said vertical position at all points along the travel of the chains.

14. In an Axminster loom wherein the pile tufts are applied to the fabric from the upper side thereof, endless spaced transporting chains, a tube frame extending between and supported by the chains and having tuft tubes extending downwardly therefrom at all times, upper and lower guides over and under which, respectively, the chains move, said guides having sprockets to engage the chains, and supports for the tube frame mounted on and movable relatively to the chains, said supports always assuming a substantially vertical position whether passing over or under the guides

with the chains and having supporting relation relatively to the tube frame regardless of the radius of the said sprockets, the weight of the tube frame maintaining the 5 supports and tube frame in said vertical position at all points along the travel of the chains.

15. In an Axminster loom wherein the pile tufts are applied to the fabric from the 10 upper side thereof, endless spaced transporting chains, a tube frame extending between and supported by the chains and having tuft tubes extending downwardly therefrom at all times, upper and lower guides over 15 and under which, respectively, the chains move, said tube frame comprising a spool and a supporting bar therebelow from which the tuft tubes depend, a carrier for each end of the tube frame, and a pivotal connection 20 between each carrier and the chain corresponding thereto, the center of gravity of the tube frame being below the pivotal connections between the carriers and the chains and acting to maintain the tube frames in 25 substantially the same position vertically as they travel around the guides.

16. In an Axminster loom wherein the pile tufts are applied to the fabric from the upper side thereof, endless spaced transporting chains, a tube frame extending between and supported by the chains and having tuft tubes extending downwardly therefrom at all times, upper and lower guides over 30 and under which, respectively, the chains move, said tube frame comprising a spool and a supporting bar therebelow from which the tuft tubes depend, a carrier for each end of the tube frame, and a pivotal connection between each carrier and the chain 35 corresponding thereto, the center of gravity of the tube frame being below the pivotal connections between the carriers and the chains and acting to maintain the tube frames in substantially the same position vertically as 40 they travel around the guides, and the axis of the spool being below the center of the pivotal connections at all times.

17. In a tuft-fabric loom, in combination with the pattern chains and their supporting 50 mechanism, a plurality of yarn frames, and rotative means on the chains for detachably interconnecting the chains and frames while permitting relative rotation between them about axes parallel with the frames.

55. 18. In a tuft-fabric loom, in combination with the pattern chains and their supporting mechanism, a plurality of yarn frames, releasable hook suspension means adjacent the frame ends and receivers therefor carried by and projecting laterally from one side of the respective chains.

19. In a tuft-fabric loom, in combination with the pattern chains and their supporting mechanism, a plurality of yarn frames, 65 and means for detachably interconnecting

the chains and frames while permitting relative rotation between them about axes parallel with the frames, said means including frame-receivers journaled on the chains at the desired intervals therealong.

70 In testimony whereof I have hereunto affixed my signature.

EDWARD J. DACEY.
